UNITED STATES PATENT OFFICE.

EDWARD ERICKSON, OF CLIFTONDALE, MASSACHUSETTS, ASSIGNOR TO VICTOR SHOE MACHINERY COMPANY, OF LYNN, MASSACHUSETTS, A CORPORATION OF MASSACHUSETTS.

LOOPER MECHANISM FOR SEWING-MACHINES.

1,243,147.

Specification of Letters Patent. Patented Oct. 16, 1917.

Application filed July 3, 1916. Serial No. 107,867.

To all whom it may concern:

Be it known that I, EDWARD ERICKSON, a citizen of the United States of America, and a resident of Cliftondale, in the county of Essex and Commonwealth of Massachusetts, have invented certain new and useful Improvements in Looper Mechanisms for Sewing-Machines, of which the following is a specification.

10 This invention relates to looper mechanisms for lock-stitch sewing machines, and has for its object the production of a device of this character which is particularly adapted to be operated at high rates of speed.

The invention consists primarily in a looper mounted in a suitable support and provided with an eye offset from the shank thereof, said looper being provided with act-

20 tuating means whereby said looper may be oscillated about the axis of said shank, and said support being also provided with means for oscillating said support about a pivot on which it is mounted.

25 The invention further consists in oscillating said looper and its support by cam mechanisms so timed that the eye of the looper will be moved in a curved path around a loop hook in one direction and then around the needle in the opposite direction.

30 The invention further consists in providing means for temporarily stopping the movement of the looper eye while the needle is moving upward with the loop and then returning the eye with increased speed to its normal position.

35 The invention consists further in certain novel features of construction and arrangement of parts which will be fully understood by reference to the description of the drawings and to the claims hereinafter given.

40 For the purpose of illustrating the invention, one preferred form thereof is illustrated in the drawings, this form having been found to give satisfactory and reliable results, although it is to be understood that the various instrumentalities of which the invention consists can be variously arranged and organized and that the invention is not limited to the precise arrange-

ment and organization of these instrumentalities as herein shown and described.

Of the drawings:

Figure 1 represents a section of a portion 55 of a sewing machine having applied thereto a looper mechanism embodying the principles of the present invention, the needle being shown in raised position.

Fig. 2 represents a front elevation of the 60 same.

Fig. 3 represents a horizontal section of the same on line 3—3 on Fig. 1.

Fig. 4 represents a partial section similar to Fig. 1 with the needle in its lowest position.

Fig. 5 represents a sectional detail of the universal connection at one end of the looper actuating link.

Fig. 6 represents a sectional detail of the 70 looper and its connection with the opposite end of its actuating link.

Figs. 7 to 10 inclusive represent diagrams showing the various positions of the looper eye in relation to the presser foot, the loop 75 hook, and the needle.

Fig. 11 represents a similar diagram showing the position of the thread when laid in the barb of the needle and before the looper eye has moved to its normal position, 80 and

Fig. 12 represents a detail of the front of the needle.

Similar characters designate like parts throughout the several figures of the draw- 85 ings.

In the drawings, 10 is a portion of the frame of a sewing machine having a hub 11 formed thereon through which extends a revoluble shaft 12. This shaft 12 has keyed 90 thereto the cam disks 13 and 14. The frame 10 is also provided with a fixed stud 15 on which is mounted the oscillating member 16 carrying a barbed needle 17, said needle having its hooked portion 18 on one side of said 95 needle, as shown in Fig. 12 of the drawings.

Pivoted at 18 to the member 16 is a link 19 through which oscillatory movement may be imparted to the member 16 from any suitable source of power. The member 16 has 100 also secured thereto a loop hook 20. The frame 10 also has secured thereto a work

support 21 having a slot 22 in a horizontal portion thereof.

The frame 10 is also provided with a headed stud 23 on which is pivotally mounted a tubular member 24. In the tubular member 24 is mounted a cylindrical shank 25 of a looper 26 having an eye 27 offset from the axis of said shank 25.

The member 24 has pivotally connected therewith at 28 one end of a link 29, the opposite end of which is pivotally connected to a lever 30 pivoted at 31 to said frame 10. The lever 30 carries a roll 32 moving in a cam path 33 in one face of the disk 14. As the disk 14 revolves in the direction of the arrow *a*, the lever 30 is moved about its pivot 31 and transmits movement through the link 29 to the member 24 and causes it to be oscillated about the horizontal pivot member 23. The lower end of the shank 25 of the looper 26 has clamped thereto the member 34 having an arm 35 extending laterally therefrom to which a link 36 is pivoted 37. The opposite end of said link 36 is connected to a rod 38 by means of the pivot pin 39 perpendicular to the pivot pin 37. This makes a universal connection between the rod 38 and the arm 35. The opposite end of the rod 38 is threaded as at 40 to a nut 41 carried by a member 42.

The threaded portion 40 of the rod 38 has also mounted thereon the nuts 43 by which the distance between the member 42 and the arm 35 may be varied, as desired. The member 42 is provided with the two parallel arms 44, between which is mounted a member 45 having a pivot pin 46 extending therethrough and into the arms 44. The sleeve 41 is adapted to revolve in the member 42 about the axis of the connecting rod 38, and the member 45 is adapted to move about the axis of the pivot member 46, said axis being perpendicular to the axis of the rod 38, thus forming a universal connection between the rod 38 and the member 45. At 47 the member 45 is pivotally connected to the upper end of a lever 48 pivoted at 49 and having a roller 50 thereon adapted to move in the path 51 of the cam disk 13. As the cam disk 13 rotates about the axis of the shaft 12 in the direction of the arrow *a* on Fig. 1 of the drawings, an oscillating movement is imparted to the lever 48 and this oscillatory movement is imparted to the rod 38 and the arm 35, and thereby causes the looper member 26 to be oscillated about the axis of its shank 25.

As the shaft 12 revolves the two disks 13 and 14 will impart movement simultaneously to the levers 30 and 48, and these movements will be transmitted through the connecting rods 29 and 38 to the tubular sleeve 24 and the laterally extending arm 35, thereby causing an oscillation of the looper member 26,

and at the same time an oscillation of the tubular member supporting said looper. These two combined oscillations cause the eye 27 of the looper 26 to move in a curved path from its normal position as indicated in dotted lines in Fig. 7 into the position indicated in full lines in Fig. 8 of the drawings, this movement passing around the loop hook 20.

The continued movement of the eye will cause the said eye to move between the loop hook 20 and the needle 17 and then move in the opposite direction around the needle into position shown in full lines in Fig. 9 of the drawings. At this point the eye comes to a standstill temporarily until the needle 17 has been raised, and then the eye 27 will be moved in a straight path with increased speed from the point shown in full lines in Fig. 9 to the point shown in dotted lines in Fig. 10.

This movement of the eye in the path shown in dotted lines in Figs. 8, 9, and 10 of the drawings causes the thread *t* to be drawn around the looper hook and then around the needle 17 in position to be seized by the hook 18 of the needle as it is raised, as shown in Fig. 11 of the drawings.

The cam paths 33 and 51 are so constructed that the necessary throws have such time relationship to each other as to cause the eye 27 of the looper to move in the curved path indicated in Figs. 7 to 10 of the drawings. The throws of the paths 33 and 51 provide for the eye 27 of the looper coming temporarily to a standstill in the position indicated in Fig. 9 of the drawings until the needle has moved upwardly sufficiently for the eye 27 to clear it, and then the cam paths act upon the actuating members to move the eye in a straight line and with increased speed to its normal position.

The position of the member 34 relatively to the shank 25 of the looper 26 may be varied by loosening the securing member 52, adjusting the member 34 about the axis of the shank 25, and then again clamping the member 34 to said shank. To accommodate this variation in the position of the member 34 about the shank 25 of the looper 26, the connecting rod 38 may be shortened or lengthened as desired by adjusting the nut 41 on the thread end 40 of said connecting rod.

Both of the connecting rods 29 and 38 are on one side of the frame 10, while the cam 13 and the lever 48 are on the opposite side of said frame, as shown in Fig. 3 of the drawings. In order, therefore, to provide means whereby the member 45 may be connected to the lever 48, an opening 53 is formed in the frame 10, as shown in dotted lines in Figs. 1 and 3 of the drawings.

This makes a very effective looper operat-

ing mechanism, which runs very smoothly and without noise, and is particularly adapted for use on sewing machines run at a high rate of speed.

5 It is believed that the operation and many advantages of this invention will be fully understood from the foregoing description.

Having thus described my invention, I claim:

10 1. In a device of the class described, a hooked needle; a looper having a rotatable shank and an eye with its axis slightly offset from and parallel to the axis of said shank; means for imparting two distinct oscillatory movements to said looper, one of said movements being about the axis of said shank and the other movement being about an axis perpendicular to the axis of said shank; and means for preventing end 15 movement of said shank.

2. In a device of the class described, a hooked needle; a looper having a rotatable shank and an eye with its axis slightly offset from and parallel to the axis of said shank; means for simultaneously imparting 25 two distinct oscillatory movements to said looper, one of said movements being about the axis of said shank and the other movement being about an axis perpendicular to the axis of said shank; and means for preventing end 30 movement of said shank.

3. In a device of the class described, a hooked needle; a looper having a shank rotatable about its axis and provided with an 35 eye the axis of which is substantially parallel to the axis of said shank and offset therefrom; means for oscillating said shank about a horizontal axis; and independent means for positively oscillating said looper 40 about the axis of said shank.

4. In a device of the class described, a hooked needle; a looper having a shank rotatable about its axis and provided with an eye the axis of which is substantially parallel 45 to the axis of said shank and offset therefrom; a cam for oscillating said shank about a horizontal axis; and another cam for positively oscillating said looper about the axis of said shank.

5. In a device of the class described, a hooked needle; a looper having a shank rotatable about its axis and provided with an eye the axis of which is substantially parallel 55 to the axis of said shank and offset therefrom; means for oscillating said shank about a horizontal axis; a laterally extending arm secured to said shank; a cam operated lever; and a link between said lever and arm.

6. In a device of the class described, a 60 hooked needle; a looper having a shank rotatable about its axis and provided with an eye the axis of which is substantially parallel to the axis of said shank and offset therefrom; means for oscillating said shank about

a horizontal axis; a laterally extending arm 65 secured to said shank; a cam operated lever; a link one end of which is connected to said lever; and a universal connection between the opposite end of said link and said arm.

7. In a device of the class described, a 70 hooked needle; a work support; a pivoted looper support inclined upwardly beneath said work support; a looper supported thereby and provided at its upper end with an eye the axis of which is offset from and substantially parallel to the axis of said shank; means for oscillating the shank about its axis; a cam controlled lever; and a link connecting said lever and said looper support.

8. In a device of the class described, a hooked needle; a work support; a tubular looper support inclined upwardly beneath said work support; a pivot therefor; a looper having a cylindrical shank extending through said tubular support and provided at its upper end with an eye the axis of which is offset from and substantially parallel to the axis of said shank; means for oscillating the shank about its axis; a cam 90 controlled lever; and a link connecting said lever and said looper support.

9. In a device of the class described, a hooked needle; a tubular looper support; a pivot therefor; a looper having a cylindrical 95 shank extending through said tubular support and provided with an eye offset from the shank thereof; means for oscillating said looper about the axis of said shank; a cam controlled lever; a link connecting said 100 lever and looper support; an arm secured to said shank; cam mechanism; and actuating means for said arm controlled by said cam mechanism.

10. In a device of the class described, a 105 hooked needle; a pivoted tubular looper support; a looper provided with a cylindrical shank integral therewith extending through said tubular support and having at one end an eye the axis of which is offset from and substantially parallel to the axis of said tubular support; means pivotally connected to said support adapted to oscillate it about its pivot; and means for oscillating the shank of said looper about its axis.

11. In a device of the class described, a hooked needle; a looper support; a pivot therefor; a looper mounted on said support and having an eye the axis of which is substantially parallel to said support and offset therefrom; means pivotally connected to said support adapted to oscillate it about its pivot; and means for oscillating the shank of said looper about its axis.

12. In a device of the class described, a 125 hooked needle; a looper support; a pivot therefor; a looper mounted on said support and having an eye the axis of which is sub-

stantially parallel to said support and offset therefrom; and cam-controlled mechanism for simultaneously and positively oscillating said support about its pivot and said looper 5 about the axis of its shank.

13. In a device of the class described, a hooked needle; an oscillating carrier therefor; a depending hook thereon; a looper having a thread eye; and means for moving 10 said looper eye from its normal position around said hook, between said hook and needle, and then around said needle to its normal position.

14. In a device of the class described, a 15 hooked needle; an oscillating carrier therefor; a depending hook thereon; a looper having a thread eye; and means for moving said looper eye from its normal position around said hook, between said hook and 20 needle, and then partially around said needle to a point at the right thereof and finally in a straight path to its normal position.

15. In a device of the class described, a hooked needle; an oscillating carrier therefor; a depending hook thereon; a looper 25 having a thread eye; means for moving said looper eye from its normal position around said hook, between said hook and needle, and then partially around said needle to a 30 point at the right thereof and finally in a straight path to its normal position; and means for retaining said eye temporarily at said right point during the upward movement of the needle.

35 16. In a device of the class described, a hooked needle; an oscillating carrier therefor; a depending hook thereon; a looper having a thread eye; means for moving said looper eye in a curved path around said 40 hook, then between said hook and needle, and then around said needle to a point at the right thereof, temporarily stopping said eye at said right point, and then moving said eye in a straight path from said point 45 to its normal position.

17. In a device of the class described, a

hooked needle; an oscillating carrier therefor; a depending hook thereon; a looper having a thread eye; means for moving said looper eye in a curved path around said 50 hook, then between said hook and needle, and then around said needle to a point at the right thereof, temporarily stopping said eye at said right point, and then moving said eye with increased speed in a straight path 55 from said point to its normal position.

18. In a device of the class described, a hooked needle; a looper provided with an eye the axis of which is offset from but substantially parallel to the axis of the shank 60 thereof; means for oscillating said looper about a horizontal axis; a laterally extending arm secured to said shank; a cam operated lever; a link between said lever and arm; and means for varying the length of 65 said link.

19. In a device of the class described, a hooked needle; a looper provided with an eye; a carrier for said needle; a depending hook on said carrier; and cam mechanisms for actuating said looper so timed 70 relatively to each other that said eye will be moved from its normal position around said hook in one direction and in the opposite direction around said needle.

75 20. In a device of the class described, a hooked needle; a looper provided with an eye; a carrier for said needle; a depending hook on said carrier; and cam mechanisms for actuating said looper so timed relatively 80 to each other that said eye will be moved from its normal position around said hook in one direction and in the opposite direction around said needle, and will be moved with increased speed from a point at the right of 85 said needle to its normal position.

Signed by me at 4 Post Office Sq., Boston, Mass., this 8th day of June, 1916.

EDWARD ERICKSON.
